UNITED STATES PATENT OFFICE

ANNA C. RATAJACK, OF CHICAGO, ILLINOIS

NECKTIE RETAINER

Application filed June 11, 1929. Serial No. 370,117.

My invention relates to neckties of the four-in-hand type and my main object is to provide a novel means to hold the front of the necktie flatly in place.

5 A further object of the invention is to anchor the tail of the necktie to the shirt without the use of special fastening or holding devices.

10 A still further object of the invention is to provide means whereby the front of the necktie may be secured by the same method as the tail.

15 Another object of the invention is to coordinate the necktie with the standardized spacing of the shirt buttons, that the latter may form the securing element for the necktie.

20 A final but nevertheless important object of the invention is to design the novel retainer in the form of but a few minor alterations of the necktie.

25 With the above objects in view and any others that may suggest themselves from the specification and claim to follow, a better understanding of the invention may be had by reference to the accompanying drawing, in which

30 Figure 1 is a front elevation of the necktie as tied and with its tail secured by the novel retainer means; and

Fig. 2 is a section of the necktie fully secured by such means.

35 In carrying out the invention, I make use of the standard four-in-hand tie, which not only has general lines of uniformity in its shape, but also is fairly standardized as to length. In coordinating the necktie with the shirt front, the idea of standardization also applies, since the size and spacing of the button holes in the fronts of shirts are uniform, due to the fact that machine means are employed to space and make buttonholes and standardization in this connection adapts the machines for use by any manufacturer of shirts.

40 The first step along the above lines is to form buttonholes "A" and "B" through the tail "C" of the necktie, these buttonholes being spaced equally with the standard spacing 45 of the shirt buttonholes "D". I also make a

buttonhole "E" in the back fold "F" of the necktie front "G".

When the wearer is about to form or tie the necktie, he will place the same within the collar with the front and tail pendent. For 55 my purpose, he will affix the tail as shown in Figure 1 over the shirt front using the button "B₁" corresponding to and protruding from the shirt buttonholes to secure the tail as clearly shown by being passed through the 60 tail buttonhole "B". With the tail anchored to the shirt front, the front of the necktie may be wrapped and otherwise maneuvered to tie the necktie with the usual knot. Then the tail is further secured by passing the 65 button A₁, through the tail buttonhole A. When this operation is finished, the front of the necktie will hang down upon the tail, and the buttonhole "E" may then be employed to anchor the rear fold "F" of the front "G" 70 upon the button "A₁" whereby to secure the necktie front with the tail to the shirt.

Since the necktie length and shirt front dimensions have been standardized as explained, it is possible for me to locate the buttonhole "E" relative to the necktie front "G" 75 at such a height that the said buttonhole will readily register with the height of the button "A₁". Also, the location of the buttonhole "E" with respect to the buttonhole "A" may be arranged so as to have the front of the necktie terminate even with the bottom of the tail or practically so when the necktie has 80 been tied and secured as described.

It will be seen that the novel retaining 85 means accomplishes several results, viz. (1) it anchors the tail of the necktie against the usual freedom of lateral deviation with movements of the wearer; (2) it fixes the position of the tail at a desired height; (3) it disposes 90 of the tail while the movements are negotiated to tie the necktie; (4) it fixes the position of the necktie front relative to the tail; (5) it secures the necktie front in proper center position and against swinging to one side or the other; (6) it secures the necktie front by concealed means so that the observer is not aware of the presence of a special retaining feature; (7) it furnishes a method for the 95 formation of the necktie with evenly grouped 100

extremities; and (8) it enables the retainer to be formed from the necktie itself and without any metallic or other adjustments, so that a minimum of alteration and labor is involved
5 and the necktie may be ironed or cleaned without any impediment whatever.

I claim:

The combination with a shirt front having standardized spaced buttons, of a necktie including a front and tail adapted to be knotted and to be disposed in pendent position over the shirt front, said tail having perforations therethrough spaced longitudinally and equally with the aforesaid buttons, and said
10 front having a buttonhole in a back fold thereof, which when the knot in the necktie is made is substantially in alignment with one of the buttons.

15 In testimony whereof I affix my signature.
